UNITED STATES PATENT OFFICE.

WALTER VAN GUILDER, OF CHICAGO, ILLINOIS, ASSIGNOR TO STEWART-WARNER SPEEDOMETER CORPORATION, OF CHICAGO, ILLINOIS, A CORPORATION OF VIRGINIA.

FIRE-EXTINGUISHING PUMP.

1,320,512.

Specification of Letters Patent.

Patented Nov. 4, 1919.

Application filed July 27, 1918. Serial No. 247,045.

To all whom it may concern:

Be it known that I, WALTER VAN GUILDER, a citizen of the United States, residing at Chicago, in the county of Cook and the 5 State of Illinois, have invented certain new and useful Improvements in Fire-Extinquishing Pumps, of which the following is a specification, reference being had to the accompanying drawings, forming a part 10 thereof.

The purpose of this invention is to provide an improved portable hand-operated pump particularly designed and adapted for use as a fire extinguisher, that is to contain a fire 15 extinguishing liquid, or material which will produce such liquid, to be discharged by means of the pump. The invention consists in the elements and features of construction shown and described as indicated in the 20 claims.

In the drawings:

Figure 1 is a vertical axial section of the pump embodying this invention.

Fig. 2 is an axial section, in a plane at 25 right angles to that of Fig. 1, of the discharge end portion of the pump barrel showing the movable piston at the discharge end of its stroke.

Fig. 3 is a detail section on the line 3—3 30 of Fig. 1.

Fig. 4 is a section on the line 4—4 of Fig. 1.

Fig. 5 is a detail top plan view of a portion of the barrel, reservoir and exterior elevation of the piston operated member at the 35 position of the parts occupied at the end of the piston in-stroke.

Fig. 6 is a section at the line 6—6, on Fig. 1.

40 The pump described in this invention is characterized in general by comprising two telescoping barrels, one of which constitutes the member for operating the piston which reciprocates in the other between two heads 45 fixed with respect to said other barrel, said piston-operating barrel having its outer end closed, so that the two barrels and the said heads and piston comprise three chambers, one between one of the heads and the piston, 50 the other between the piston and the other head, the third between said other head and the closed end of the piston-operating barrel; the connections and communication of the parts being such as to cause two of said

chambers to be filled by suction at the extending stroke, while the third chamber is evacuated at that stroke, the opposite stroke causing the last-mentioned chamber to be filled and the two first mentioned chambers to be evacuated, so that there is both a filling and an evacuation at each stroke in each direction. It is further characterized by the mounting upon the outer or fixed barrel of a reservoir from which the liquid to be pumped is drawn, a suction pipe extending from the barrel to the bottom of said reservoir, and the reservoir being projected downward from the barrel and adapted to serve as a handle for holding the pump 55 while operating it.

In the drawings, 1 is the outer or fixed barrel, 2 the inner or telescoping barrel which is the piston-operating member having its inner end connected to the piston. 3 is the laterally extending reservoir which 60 serves as a handle for the device; 4 is a fixed head in the barrel 1 near the discharge end, said discharge end being provided with a mouth-piece or nozzle 17 in which there is mounted a spring-seated stopper 19 for preventing the discharge or leakage from the device when it is not in use as is hereinafter 65 more particularly explained. 5 is the second head, fixedly positioned in the barrel 1 near the opposite end thereof from the head 4, 70 said head 5 being of the character of a piston with respect to the barrel 2, and being held fixed with respect to the barrel 1 by means of two tubes 6 and 7 which connect it 75 with the head 4, and which have functions 80 hereinafter specified. The end of the barrel 2 opposite the discharge end of the barrel 1 is closed by a cap 10 which is preferably 85 inclosed in a hand-piece 11, which is a thin metal shell pear-shaped in general form 90 which telescopes outside the barrel 1 and is provided with a close fitting engagement therewith at its inner end by means of a ring 12 angular in cross section, one cylindrical flange of which makes a sliding fit on 95 the outside of the barrel while the other is engaged by the inner end of the hand-piece 11 which is folded around it as shown in the drawing. The reservoir 3 which as to its main portion is preferably substantially 100 cylindrical and of convenient diameter to be readily grasped by the hand of the operator, is preferably expanded at its upper end 105

where it is penetrated by the barrel 1. The latter is rigidly mounted therein and properly secured against leakage where the barrel penetrates the reservoir. The reservoir 5 is mounted on the barrel so as to bring the head 4, or the main portion thereof, within the reservoir; (that is, the portion of the barrel in which the head is positioned is within the reservoir) so that the suction tube 10 20 which leads from the bottom of the reservoir for conducting the liquid into the pump, may be connected as shown in the drawing, into the barrel 1 at a point which will cause the tube to connect with a radial duct 21 in 15 the head 4, through which the liquid drawn in by the pumping operation from the reservoir, is conducted into the chambers of the pump, as more particularly hereinafter described. The two tubes 6 and 7 which connect the heads 4 and 5 are concentric, the former within the latter. The exterior tube 20 25 30 35 40 45 50 55 60 65 70 75 80 85 90 95 100 105 110 115 120 125 130 135 140 145 150 155 160 165 170 175 180 185 190 195 200 205 210 215 220 225 230 235 240 245 250 255 260 operation of the device is, therefore, that of the three chambers, two are filled by two in-drawn streams of liquid in the retracting stroke of the piston-operating member, 5 while one is emptied by discharge through the central tube; and in the opposite stroke, the two which are first filled are emptied by two separate discharges, one through the central tube 6 and the other through the duct 26 in the head 4, while one is filled by liquid flowing in through a single course. The result is that both strokes are equally easy, the amount of work done in each of the two strokes being substantially the same, 10 although the quantity discharged is substantially twice as great at the in-thrust stroke as at the retracting stroke. It will be noticed that the mouth-piece has a restricted discharge mouth 17^a, so that the liquid will be discharged in a slender jet, and thereby may be thrown to a very considerable distance; and in view of the fact above mentioned, that the double quantity is discharged at the in-thrust stroke, it will follow that at the in-thrust stroke, the work being more largely expended on the discharge than on the intake, the double quantity discharged through the discharge orifice by a stroke as rapid as —and no more rapid than,—the retracting 15 stroke, will be projected much more forcibly and to a greater distance. And upon reflection it will be seen that this is not undesirable, since it is more natural to aim and attempt to reach a distant target by a thrust than by pull or retracting movement, and the operator will naturally rely upon his thrust stroke for reaching the more distant points or those which he wishes to reach with the greatest force.

20 Since the material which a pump of this character is designed to employ, namely, material for extinguishing fires, is liable to expansion and vaporization, it is important that the discharge mouth should be at all 25 times closed when the device is not in use, and this is desirable even if only to prevent leakage of liquid, and for this purpose the stopper-valve 19 is provided for closing the discharge orifice 17^a and is normally held retracted from that orifice by means of the spring 18. This valve is mounted upon two stems 19^a—19^a which obtain guidance in the head 4, extending through the head so as to expose their inner ends in the path of the piston 8 which strikes them as it approaches the head 4 and forces the stopper-valve to its seat, closing the orifice as the piston reaches the inner end of its stroke.

25 For the purpose of locking the parts in inoperative position, that is with the two barrels fully telescoped together, the collar 12 is provided at opposite sides of the barrel member 2 with opposite turned hooks 12^a, and there is mounted on the side of the reservoir or in the angle between said reservoir

and the barrel 1 where the latter protrudes from the reservoir at the rear side, a flange 34 which has inwardly turned hooks 34^a, under or behind which the hooks 12^a may become engaged by turning the entire telescoping barrel member 2 through a few degrees about its axis when it has been first thrust into the fully telescoped position.

I claim:

1. A portable hand pump comprising in combination with a pump barrel, a piston member telescoping withing the barrel and a handle for operating said piston member which incloses the outer end thereof and which telescopes outside the barrel.

2. A portable hand pump comprising in combination a pump barrel, a reservoir projecting off transversely from the barrel, a piston member telescoping in the barrel, a suction pipe leading out from one end of the barrel into the reservoir and opening into the bottom part of the latter, the reservoir being penetrated by the barrel so that the reservoir cavity extends around the barrel, the reservoir having an air vent aperture at the top and an inwardly-opening spring-seated valve at the aperture.

3. A double acting pump comprising a barrel having a discharge mouth and a suction intake, two heads longitudinally separated a fixed distance from each other in the barrel, a movable piston in the barrel between the heads, and a piston-operating member extending from one end of the barrel past one of the heads to engage the piston, an intake tube and a discharge tube connecting the two heads, duct connections in one head from the tubes respectively to the chamber of the barrel between the piston and said head, the two tubes being connected respectively through the other head with the suction intake and the discharge mouth.

4. A construction such as defined in claim 3, the two tubes being concentric.

5. A double acting pump comprising a barrel having a discharge mouth and a suction intake, two heads longitudinally separated a fixed distance from each other in the barrel, a movable piston in the barrel between said two heads, a tubular piston-operating member telescoping in the barrel and extending past one of said heads to engage the piston, said head operating as a piston in said tubular piston-operating member and having two passages for communication from one side of said head to the other side, an intake tube and a discharge tube connecting the two heads, one of said passages having communication with one of the tubes, and the other of said passages having communication with the other tube, and valves controlling said passages to determine whether said tubes communicate with one side or the other of

the head having said passages, according to the direction of movement of the movable piston.

6. A pump for manual operation comprising two telescoped barrels one of them having an intake connection and having at one end a discharge mouth-piece, the opposite end of the other tube being closed; two longitudinally separated heads fixed with respect to the first mentioned barrel, a piston fixed with respect to the other barrel and positioned between said two heads;

tubes which rigidly connect the two heads and along which the piston reciprocates between said heads, one of said tubes leading 15 to the discharge mouth-piece and the other to the intake connection; and valves controlling the passages for causing movement through said tubes in the directions for discharge and intake respectively. 20

In testimony whereof, I have hereunto set my hand at Chicago, Illinois, this 24th day of July, 1918.

WALTER VAN GUILDER.
